Marie F. Anderson
ATTORNEY

UNITED STATES PATENT OFFICE

LOUIS E. PERKINS, OF RICHMOND HILL, NEW YORK, ASSIGNOR TO FREDERICK PERKINS, OF NEW YORK, N. Y.

LANTERN

Application filed February 2, 1927. Serial No. 165,357.

This invention relates to lamps and is more particularly directed to lanterns of improved construction such as marine lanterns lighted by means of oil, gas, or electricity.

5 An object of the invention is to provide an improved device of the character described having a casing of novel construction forming a rigid structure free from soldered joints.

10 Another object of the invention is to provide a portable or marine lamp of improved construction and having a novel opening and closure therefor to permit of ready access to the interior of the lamp for safe and easy 15 manipulation or removal of the light providing means, while at the same time preserving at its maximum the uniform lighting quality and usefulness of the lamp.

Still another object of the invention is to 20 provide a lamp of the character described having a longitudinally split cylindrical globe, a portion of which serves as a hinged closure for the improved device.

A further object of this invention is to 25 provide a lamp of the character described having a "Fresnal" type of globe, a wall portion of which is movable to permit of access to the interior of the lamp, said wall portion being then returnable to its normal position 30 to provide the desired lens effect with the light.

A still further object of the invention is to 35 provide a lantern of the character described of improved construction comprising few and simple parts which are assembled to form a rugged yet neat appearing structure, which shall be relatively cheap to manufacture, and practical and efficient to a high degree in use.

Other objects of this invention will in part 40 be obvious and in part hereinafter pointed out.

The invention accordingly consists in the 45 features of construction, combinations of elements, and arrangement of parts which will be exemplified in the construction hereinafter described, and of which the scope of application will be indicated in the following claims.

In the accompanying drawing, in which is 50 shown one of the various possible illustrative embodiments of this invention,

Fig. 1 is a view in elevation of a lantern embodying the invention.

Fig. 2 is an enlarged view in section taken approximately on line 2—2 of Fig. 1.

Fig. 3 is an enlarged view in section on line 55 3—3 of Fig. 1, dotted lines indicating the open position of the closure member.

Fig. 4 is a fragmentary cross-sectional view taken on line 4—4 in Fig. 1.

Fig. 5 is a fragmentary sectional detail 60 view of a modified construction of the draft-tight joint between the lens portion.

While the invention may be applied to lighting devices using oil, gas, or electricity, the lantern disclosed herein as shown is of 65 the oil burning type adapted particularly for marine service.

The lantern is shown as comprising a casing H of improved heat resisting construction, and a tubular globe formed preferably 70 with a "Fresnal" type of lens L of novel and improved structure and utility. The lantern is of very strong and rugged construction throughout to withstand the hard use and wear to which it may be subjected. Thus the 75 casing is made of practically rust-resisting sheet metal such as brass having joints formed in a reliable manner, while the lens or tubular globe is made of thick glass.

The casing includes a plurality of coacting 80 members or parts having joints which preferably are united without solder. Said parts may be pressed, spun or cast, and joined together by seams, rivets or screw connections whereby a rigid structure is formed that will 85 withstand any overheating of the lantern in use without affecting the joints.

Referring more specifically to the drawing, the lantern includes a cylindrical supporting receptacle 10 having a closed bottom 10^a, and arranged to receive coaxially therein an oil fount 11 having a conventional burner B provided with a flame adjusting screw 12. Bayonet connections 13 comprising a slotted member 13^a riveted as 90 shown at 14 to the receptacle bottom 10^a and pins 13^b outwardly projecting from the fount 11 which engage said member 13^a; said bayonet connection has cooperating therewith an upwardly acting spring 15 secured to the 95 100

bottom of the fount which detachably retain the latter in position. Openings 16 in the wall of said receptacle permit the entrance of air, which is baffled by a cylindrical plate 17. An annular ring frame 18 which serves also as a globe supporting means, as will be described hereinafter, is provided at the top of said receptacle. The receptacle 10, plate 17 and frame 18 have parallel contacting flanges 10^b, 17^a and 18^a, respectively, the flange 18^a being beaded over as at 18^b to form a solderless clamping seam for rigidly joining said flanges together.

The top portion of the lantern is terminated by a ring handle 27 and includes a hood 19 having air outlets 20 and a coacting frustoconical baffle plate 21 to insure a uniform draft. The hood 19 is joined by means of a seamed connection 23 to an annular member 22; and the baffle plate 21 has an annular bead 24 adjacent the connection 23 for mounting said plate in position to form a reliable and air tight joint, as is clearly shown in Fig. 2. The member 22 is formed with a lower rim flange 22^a which engages a ring frame 25, the latter being similar in structure and serving the same purpose as the frame 18 described above. Said frame 25 has an annular flange 25^a superimposed on the flange 22^a of the member 22. These flanges 25^a and 22^a are rigidly clamped together preferably by a bead 26 extended from the flange 22^a to form a solderless seamed joint.

The top portion of the lantern and said receptacle are firmly interconnected by spacing rods 29 which have their ends secured to the clamped flanges of said top lantern portion and said casing by means of screws 30 passing therethrough. It is thus seen that all connections herein provided for are solderless whereby overheating of the casing, lantern top and globe will not cause the seamed joints to open, thus practically eliminating possible fire hazard.

The globe or lens L here is of tubular cylindrical form and is split longitudinally preferably diametrically at 31 and 32, a semi-cylindrical portion 33 thereof being and forming a closure, which in open position 50 permit the removal and replacement of the oil fount and burner to facilitate filling, cleaning or adjustment without necessitating tipping of the fount, thus preventing accidental spilling of the oil. The other portion 34 of the globe is stationary being retained in position by upper and lower arcuate frame members 35 which are secured between the ends of the rods 29 at the clamp flanges of the casing and the lantern top portion. The movable lens portion 33 forming the closure or door, is mounted upon a frame including upper and lower horizontally extending arcuate members 36 joined by connecting rods 37 and screws 38 having their heads countersunk into the members 36. The members 36

have arcuate slots 39 into which the adjacent rim edges 33^a of the lens portion 33 are snugly fitted, the end corners of the glass being undercut at 40. As shown in Figs. 2 and 3, the door frame carrying the lens portion 33 is swingably mounted on one of the rods 29 as at 36^a on one end of each member 36, while a locking device such as pivoted latches 41 is provided adjacent the other ends of the member 36. Each latch has notched ends 41^a adapted to engage an adjacent end on the fixed portion of the lantern rod 29 and a finger-piece 41^b for manipulation of the latch. When the closure is in locked position, the inner edges of the arcuate members 36 abut the rings 18 and 25, as shown in Fig. 4, and the closure will then be substantially draft-tight.

To make a draft-tight joint between the split portions of the lens, the vertically extending edge faces of the lens portion 33 may be provided with projecting rib extensions 33^b adapted to fit into vertically extending grooves 34^a formed in the edge faces of the lens portion 34 which normally abut the edge faces of the lens portion 33.

In Fig. 5 is shown a modified form of draft-tight joint for the lens portions 33 and 34. Here, grooves 134 are provided in the lens portion 34. Said grooves are adapted to retain a suitable resilient material 100, such as an asbestos packing, the portion of said packing extending outwardly from the edge faces of said lens portion forming gaskets for abutting the edge faces of the lens portion 33.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. In a lantern, the combination of a casing, a globe supported in the casing comprising a plurality of contiguous, contacting sections arranged in the casing to form a tubular member, one of said sections being movably secured to the casing to form a closure therefor, and means for providing a draft-tight joint between said movable section and the section adjacent thereto.

2. In a lantern of the character described, a casing having a receptacle portion adapted to hold a light source, said portion comprising a wall having air-inlet openings, a baffle member interposed between said wall and said

source, a globe surrounding said source, and a frame member on said portion for securing the globe in position thereon, said frame member baffle and wall of the receptacle portion each having flanges abutting one another, said frame flange having a portion bent over the edge portions of said baffle and wall flanges to form a solderless joint for securing said frame member, baffle and wall together.

5 10 3. In a lantern of the character described, the combination of a cylindrical casing and a globe split to form a stationary portion supported by the end walls of said casing, and a movable portion, said casing including means 15 for supporting said movable portion for swinging movement.

4. A lantern of the character described, comprising a glass tubular globe split to form a stationary portion and a movable portion, 20 lens integrally formed in the globe structure, a cylindrical casing supporting said globe between the end walls thereof including a member to swingably support the movable portion, and means to effect a draft-tight 25 closure between the abutting portions of the globe and between said movable portion and the casing.

5. In a lantern of the character described, the combination of a glass tubular globe split 30 longitudinally to provide a stationary portion and a movable portion, a lens integrally formed in the globe structure, and a cylindrical casing supporting the globe including a member to swingably support the movable 35 portion, the frame members forming part of said casing and cooperating with the stationary portion to retain the latter in position and contacting with the movable portion in its closed position to provide draft-tight 40 joints.

6. In a lantern of the character described, the combination of a tubular globe split longitudinally to provide a stationary and a pivotally movable portion, and a cylindrical 45 casing including end frame members for retaining the stationary portion in position, said end members forming an abutment for the movable portion at the edge portions thereof, when said movable portion is in closed position.

50 7. In a lantern of the character described, the combination of a hollow glass cylindrical globe split longitudinally to provide a stationary portion and a movable portion, a lens integrally formed in the globe structure, and a frame for the movable portion including upper and lower curved members having arcuate slots in which opposite edges of the movable portion are seated.

60 8. In a lantern of the character described, the combination of a glass tubular cylindrical globe split longitudinally to provide a stationary portion and a movable portion, a lens integrally formed to extend around said portions, and a casing for the globe including

upper and lower portions, connecting rods to join the same together, a frame for the movable portion including upper and lower arcuate members having arcuate slots into which edges of the movable member extend, and 70 rods joining said members of the frame together, said frame being swingably mounted between the upper and lower portions of the casing.

75 In testimony whereof I affix my signature.
